UNITED STATES PATENT OFFICE.

CHARLES H. BLACK, OF SCOTTDALE, PENNSYLVANIA.

SAFETY PROTECTIVE ENVELOPE.

Application filed April 18, 1922. Serial No. 554,644.

To all whom it may concern:

Be it known that I, CHARLES H. BLACK, a citizen of the United States, residing at Scottdale, in the county of Westmoreland and State of Pennsylvania, have invented 5 certain new and useful Improvements in a Safety Protective Envelope, of which the following is a specification.

This invention relates to envelopes.

10 The main object of the invention is to provide an improved envelope which, when sealed, cannot be opened without being mutilated so as to show that it has been opened.

15 A further object is to provide an envelope of this character that is more conveniently and easily sealed than other envelopes of this character.

20 A further object is to provide an envelope of this character that is constructed of a single blank of paper or other sheet material, at a low cost, and is substantial and thoroughly practical.

25 Other objects and advantages will be pointed out or implied in the following details of description, in connection with the accompanying drawings in which:

Fig. 1 is an inner side view of the blank from which my improved envelope is formed.

30 Fig. 2 is a view showing the envelope partly closed but not sealed.

Fig. 3 is a view showing the envelope closed and sealed.

Fig. 4 is a sectional view on the line 4—4 35 of Fig. 3.

Fig. 5 is a sectional view on the line 5—5 of Fig. 3.

Fig. 6 is a view illustrating a modified form such as known as the open-end envelope.

40 Referring to these drawings in detail, in which similar reference characters correspond to similar parts throughout the several views: The invention consists in the construction and arrangements which will now be fully described in the following:

This envelope includes five main sections, 1, 2, 3, 4 and 5, the latter being the top section or closure; and the other four sections 45 forming the pocket to be closed by the closure 5. The pocket is formed by folding the blank (Fig. 1) along the fold-lines 6, 7 and 8 so as to bring the end sections 3 and 4 onto the intermediate section 1, and to bring the 55 lower section onto the sections 3 and 4.

"Gum" or adhesive substance is provided at 9, on the end sections 3 and 4, and when these sections are secured, by this adhesive substance, to the section 2, these three sections form the rear wall of the pocket. An opening or space 10 is provided between the inner ends of the sections 3 and 4 and above the upper end of the section 2, for an important purpose, as will presently be seen.

The closure 5 includes three sub-sections 60 or gummed flaps 11 and 12, the latter being between the two similarly constructed and gummed flaps 11. The gum or adhesive substance of these flaps 11 is applied to the inner surface, as shown at 13, so that when moistened and pressed on the outer surface 65 of the rear wall, they will adhere thereto and seal the envelope in the usual way; but the flap 12 is "gummed" in its outer surface, as shown at 14; and this flap 12, in connection 70 with the recess or opening 10, constitutes the safety feature of this device. This feature is made prominent by the presence of notches 75 15 at opposite sides of the flap 12; for these notches receive the upper edge of the section 2 and combine therewith to make a close-fitting interlocking joint between the lower part 80 of the closed section 5 and the rear wall of the pocket. The upper end of the opening 10 merges with the opening of the pocket of 85 the envelope, so that no difficulty is experienced in quickly inserting the tongue or flap 12 in this opening and thence extending it 90 into the pocket.

In sealing the envelope, its flaps 11 and 12 90 first have their gummed surfaces moistened, then the flap 12 is bent inwards so that its gummed surface is against the inner surface of the rear wall, while the gummed surfaces 95 of the flaps 11 are against the outer surface 95 of the rear wall. Therefore, when the gum or adhesive dries or "sets" the section 5 is not only interlocked with the rear wall of the pocket, but also glued or cemented to both the inner and outer surfaces of the 100 pocket.

It will be noted that the flaps 11 are provided with curved edges, leading from the notches 15, which curved edges eliminate sharp corners or points on said flaps adjacent the tongue or flap 12. Such sharp points have been found in the actual handling of mail to be a source of considerable annoyance and inconvenience to the mail 105 clerks, due to the fact that they are seldom 110

securely sealed down, and consequently have a tendency to catch in adjacent pieces of mail.

It will further be noted that the flaps 11 extend down over the uppermost edge of the section 2 of the pocket, and are secured thereto, thereby effectively preventing the undetected opening of this lower section, which might be accomplished if this were not the case. Furthermore, due to the fact that the flap 12 is gummed on the outside, rather than on the inside, it is secured to the inner surface of the envelope pocket, and while preventing the undetected opening of the envelope, it in no wise interferes with the ready removal of the contents of the envelope by the proper party.

It is not intended to limit the invention to the exact construction and arrangement shown in Figs. 1 to 5, but changes may be made within the scope of the inventive idea, as implied and claimed; for instance, I may eliminate part of the gum or adhesive, as in Fig. 6, so that when the envelope is sealed at

its intermediate part, its ends, or either one 25 of the ends, may be opened as is the ordinary open-end envelope.

What I claim as my invention is:

An envelope the pocket of which includes a rear wall formed of two inwardly turned end sections and an upwardly turned lower section, this rear wall also including a space between said end sections and above said lower section, and a closure including three securing flaps, two of said flaps overlapping the lower sections of the rear wall and provided with means for securing them to the outer surface of said rear wall at opposite sides of said space, the third one of these securing flaps being insertable in said pocket through said space with its base abutting the upper edge of the lower rear wall section and provided with means for securing it to the inner surface of said pocket.

In testimony whereof, I affix my signature.

CHARLES H. BLACK.
